UNITED STATES PATENT OFFICE.

FRANK SHLEHTEC, OF MINNEAPOLIS, MINNESOTA.

IN AND OUT INDICATOR.

Application filed November 5, 1925. Serial No. 66,983.

My invention has for its object to provide an extremely simple and highly efficient "in and out" indicator, intended for general use, but especially adapted for hospitals for containing a list of the doctors, nurses and other attendants to indicate whether they are "in or out" of the hospital.

To the above end, generally stated, the invention consists of the novel devices and combinations of devices hereinafter described and defined in the claim.

In the accompanying drawings, which illustrate the invention, like characters indicate like parts throughout the several views.

Referring to the drawings:

Fig. 1 is a front elevation of the indicator with some parts removed, and with one of the doors open;

Fig. 2 is a view principally in vertical section, taken on the line 2—2 of Fig. 1;

Fig. 3 is a view principally in horizontal section, taken on the line 3—3 of Fig. 1, with both doors closed; and

Fig. 4 is a perspective view of one of the carriers removed from the cabinet.

The numeral 5 indicates a cabinet having a central vertical partition 6 dividing said cabinet into two compartments 7, each of which is closed by a hinged door 8 having a transparent panel. In each compartment 7 is a plurality of horizontally extended vertically spaced carriers, each of which has a flat rectangular body 9 from the ends of which project axially aligned trunnions 10 and 11. The trunnions 10 are journaled in seats in the partition 6 and the trunnions 11 are journaled in seats in the sides of the cabinet 4 and extend outward thereof. To the projecting outer end of each trunnion 11 is applied a finger piece 12 having a bore-like recess into which the respective trunnion 11 projects and to which said finger piece is detachably secured by a wood screw 13.

The end of each body 9 at its trunnion 11 is reduced and made square in cross section to afford upper and lower stop surfaces 14. Secured to the back of the cabinet 4 is a spring 15 for each carrier 9. These springs 15 rest on the upper stop surfaces 14 and yieldingly hold the carriers set vertically edgewise. By giving the finger pieces 12 a one-half turn, either flat vertical face of the carriers 9 may be turned outward so that they are visible through the doors 8. To each vertical face of each carrier 9 is secured a holder 16 for detachably holding a name plate 17. The name plates 17 on each carrier have the same name but on one thereof is indicated the word "In" and on the other thereof is indicated the word "Out".

From the above description, it is evident that by turning the carriers 9, the same may be set to indicate whether the person whose name appears thereon is "in or out".

The improved indicator while extremely simple and of comparatively small cost to manufacture, has in actual usage proven highly efficient for the purpose had in view.

What I claim is:

In an "in and out" indicator, the combination with a cabinet, of a carrier formed from a single piece of material and comprising a rectangular body member having formed with its ends trunnions journaled in the cabinet, one of said trunnions having upper and lower stop surfaces, a horizontal spring attached to the back of the cabinet and arranged to bear on the trunnion having the stop surfaces and be alternately engaged by said stop surfaces under a turning movement of the carrier to stop and yieldingly hold the same with either of its faces out, a holder on each face of the body member, and a thumb piece detachably applied to one of said trunnions outside of the cabinet.

In testimony whereof I affix my signature.

FRANK SHLEHTEC.
